UNITED STATES PATENT OFFICE.

SAMUEL W. WHITMORE, OF CLEVELAND, OHIO.

PROCESS OF REFINING OILS.

1,125,422.

Specification of Letters Patent.

Patented Jan. 19, 1915.

No Drawing.

Application filed March 28, 1914. Serial No. 827,908.

To all whom it may concern:

Be it known that I, SAMUEL W. WHITMORE, a citizen of the United States, resident of Cleveland, county of Cuyahoga, and State of Ohio, have invented a new and useful Improvement in Processes of Refining Oils, of which the following is a specification, the principle of the invention being herein explained and the best mode in which 5 I have contemplated applying that principle, so as to distinguish it from other inventions.

My invention relates to the distillation of crude petroleum or certain of its products and has for its object the making from 15 certain kinds of crude petroleum of inferior quality or certain of the products thereof, commercial products of higher grade, and in a more economical manner, than have heretofore been obtained by methods at 20 present used, in so far as I am aware.

As is well known, the supply of crude petroleum, similar to that which is known as Pennsylvania crude, is continually becoming scarcer and more expensive, and my 25 invention has for a specific purpose the refining of inferior crude oils such as are found in the Lima fields, with the production of commercial products by more economical methods than those at present used, 30 and especially with the production of heavy distillates for lubricating purposes from such inferior crude oils, that are free from objectionable odors and hence of great commercial importance. Incidentally my invention 35 contemplates the treatment of such crude oil and its products without the necessity of materially changing the existing style of equipment or apparatus and concurrently without the necessity of changing 40 materially the simple process of distillation now and for so long a time and so economically employed in the distillation of Pennsylvania crude oils. It is also desirable, as will be readily understood, and 45 as is now well known, to obtain from the crude petroleum commercial constituents having the highest degree of absence of impurities and in the case of gasolene, benzin and illuminating oils in addition the highest 50 est possible degree of clarity or whiteness in appearance.

In carrying out my invention as applied to crude oils of lower grade such as Lima crude, the latter are treated with naphthalene while being subjected to what is known as the Pennsylvania process. This Penn-

sylvania process consists in placing the crude petroleum in the still and then applying heat thereto continuously for a given length of time. This application of heat 60 effects the distillation of the various constituents in the order of their volatility, the lighter constituents such as gasolene being first given off, followed by the next heavier constituent, as benzin, and then the water 65 white distillates or illuminants. The remaining substance or residuum in the still, in the case of these latter petroleums, consists chiefly of lubricating oils and paraffin or asphaltum. These distillates are successively 70 condensed and led into separate receptacles or tanks by means of apparatus well known to those skilled in the art and after separation are collected, and then treated by agitation with sulfuric acid for 75 the purpose of clarification. After this treatment the bulk of the acid is separated and the oil then neutralized with a solution of caustic soda after which it is washed with water by means of a suitable agitator. 80

In applying my improved process to the low grade crude oils, I add naphthalene before distillation in the proportion of from five hundred (500) to eight hundred (800) pounds for every five thousand (5000) gallons of crude petroleum. The resulting distillates are found to be of a greatly improved quality as compared with those produced by simple distillation, in that their odor is greatly improved and their color 90 lighter by a marked degree. This is true to such an extent in regard to the odor as to render unnecessary the customary method of treating such distillates by adding a caustic solution of lead compounds, or of 95 distillation with copper oxid, or other similar methods, marketable products being obtainable after applying my said process by simply washing with acid and soda as previously described. 100

The effect of my improved treatment is particularly noticeable in the heavy distillates and heavy residuum of distillation which are commonly used for lubricating purposes, as these are found to be sufficiently 105 good in quality as to odor and other required qualities to be used for lubricants without further treatment.

As to the burning-oil distillates, my improved process results in producing water 110 white and other oils for illuminating uses superior, not only in clarity, odor, and can-

dle power, but in freedom from effecting wick incrustation. For instance it has been shown that these oils continue to produce as high or even higher candle power after long continued burning tests, than is produced from similar grades of Pennsylvania distillates, and are far superior in light producing qualities to similar distillates from inferior grades of crude petroleum, when 10 treated in accordance with my invention.

In establishing the above facts I have caused burning tests to be applied to distillates made by my process and to similar distillates from the same crude oil made in 15 the same manner but without the addition of naphthalene, as well as to samples of distillates obtained in the open market and made from Pennsylvania and Illinois crude oils. These tests show the following losses of 20 candle power upon continuously burning in lamps, water white samples of the various above mentioned oils for a period of ten hours, the illuminating power at the start being taken as 100 per cent.: from Lima 25 crude distilled with naphthalene, twenty-six per cent. (26%); from Lima crude not distilled with naphthalene, sixty-one per cent. (61%); from Illinois crude (market product), forty-three per cent. (43%); from 30 Pennsylvania crude (market product), fifty-three per cent. (53%). I have also found that I can advantageously treat heavy distillates or residuums from crude petroleums of inferior quality and obtain commercial products of great value therefrom, 35 by simply heating such distillates or residuums with naphthalene in a proportion of one (1) pound of naphthalene with five (5) to ten (10) gallons of oil with a temperature 40 of 200° to 400° F. Such products derived by ordinary distillation from these crude

oils are ordinarily worthless for commercial purposes without further treatment, because of their extremely disagreeable odor. This odor, by my process, is entirely removed 45 and the products rendered in every way equal to those obtained from the best grades of Pennsylvania crude oil by the usual process.

I am aware that naphthalene has been 50 heretofore used in treating illuminating oil by simply mixing and gently heating same with such oil, for the purpose of increasing the illuminating power of the latter, but in so far as I am aware, naphthalene 55 has never heretofore been applied to the refining of crude petroleum, nor has it ever been used as an element for sweetening ill-smelling distillates and especially lubricating oils or heavy residuums. 60

Having fully described my invention, what I claim and desire to secure by Letters Patent is:—

1. The process of separating hydrocarbon oil into its constituent elements which consists in first adding thereto naphthalene, and then subjecting the resultant mixture to the process of distillation. 65

2. The process of separating hydrocarbon oil into its constituent elements which consists in adding naphthalene thereto in the proportion of from five hundred to eight hundred pounds to five thousand gallons of hydrocarbon oil; and then subjecting the resultant mixture to the process of distillation. 70 75

Signed by me, this 27th day of March, 1914.

SAMUEL W. WHITMORE.
